UNITED STATES PATENT OFFICE.

JUSTUS J. ROSS, OF HUNTINGTON, WEST VIRGINIA.

METAL MINE TIE.

Application filed March 19, 1924. Serial No. 700,353.

To all whom it may concern:

Be it known that I, JUSTUS J. Ross, a citizen of United States, residing at Huntington, in the county of Cabell and State of West Virginia, have invented certain new and useful Improvements in Metal Mine Ties, of which the following is a full, clear, and exact description.

The invention relates to metal mine ties and one of the objects of the invention is to provide a device of this character which is inexpensive in manufacture, and yet which possesses sufficient strength and durability to withstand the severe usage to which it is subjected.

Another object of the invention is to provide a tie which will securely clamp rails of various sizes without altering the gauge of the track.

Another object of the invention forming a material part of the present application is to provide a novel anchoring means by which movement of the tie in any direction is prevented.

Further objects and advantages of the invention will be apparent from the following detailed description when taken in connection with the accompanying drawings; in which,

Figure 1 is an elevational view of the tie, parts being in section, and showing a section of a large rail clamped in position, and also showing a small rail in dotted outline.

Figure 2 is a fragmentary plan view of the tie with a rail in position, and

Figure 3 is a detail perspective view of a portion of the tie with the anchoring means detached.

Referring to the drawings more in detail, numeral 1 indicates the body of the tie, which has a flat top surface and downwardly extending flanges 2 on each side thereof; that is, the body of the tie has the cross-sectional shape of channel iron. These flanges possess a dual function, in that they add considerable strength to the tie and at the same time they act as an anchoring means to prevent any lateral movement of the tie.

The ends of the tie are turned upwardly and inwardly to form hook shaped ends as indicated by numeral 3; and wooden wedges 4 are inserted between the hooked ends and the rails to force the latter into place.

A novel form of clamping lug is indicated

by numeral 5. The specific form of the clamping lug forms the subject-matter of a separate application, but its construction and operation will be briefly described herein. In Figure 1, I have shown in section relatively large rails clamped in position, and in dotted outline is shown a small rail clamped in position. Rails are composed of three parts, the head, the web, and the flange, and these parts are indicated by the numerals 6, 7, and 8, respectively for the large rails; and by numerals 6', 7', and 8', respectively, for the small rails. The clamping lug 5 has a flat portion 9 coinciding with the flat surface of the tie, and an upwardly inclined portion 10 for engaging the flange of the rail or the web of the rail as the case may be, depending on the size of the rail employed. The clamping lug is provided with strengthening side flanges 11, and the lug is preferably secured to the tie by means of rivets.

The clamping lug 5 is so designed that when it is employed with the largest rails commonly used in mine work, it will follow the contour of the rail flange or base 8, and thus exactly fix the position of the largest rails, as clearly illustrated in Figure 1. It will be noted, however, that the lug does not extend up to the web of the rail when the larger rail is employed. If the inclined portion of the clamping lug extended up to the web when large rails were employed, then it would be obvious that when smaller rails

were employed the inclined portion would also strike the web and hold both the small and large rails in the same position, thus altering the gauge of the track. On the other hand, if the inclined portion was so

designed that it was much shorter than illustrated herein, then when a small rail was used, its flange would be forced under the lug until it contacted with the inclined portion at the point where the lug meets the surface of the tie, and consequently there would be considerable variation in the gauge. The clamping lug is not so designed,

however, and by an inspection of Figure 1 it will be seen that when a small rail is employed the web 7' abuts against the free end of the inclined member, and when a large rail is employed the web does not contact with the inclined member at all, but the flange of the larger rail contacts with the inclined member at the point where the lug

meets the surface of the tie. By this construction the vertical center line of the rail is moved only slightly for different size rails, and this difference in position just 5 about compensates for the difference in width of the heads of different size rails, so that the gauge remains almost exactly the same.

As previously mentioned herein, the side 10 flanges 2, 2, of the tie body, in addition to strengthening the tie, also serve as an anchoring means to prevent lateral displacement. One of the material features of the present invention is to provide additional 15 means to prevent longitudinal displacement of the ties. Attached to the tie, preferably below each of the rails, is a novel form of anchoring means, as indicated by numeral 12. The anchoring means comprises a 20 short metal strip having a flat surface 13 adapted to coincide with the bottom of the tie, and downwardly extending side flanges 14 adapted to dig into the ground or mine floor and prevent longitudinal movement of 25 the tie. It will be noted that the flanges 14, 14 of the anchoring means are of greater length than the flanges 2, 2 of the tie body, so that the flanges 14, 14, will first dig into the mine floor, and will be followed by the 30 flanges 2, 2. It will also be noted that the channel iron section constituting the longitudinal anchoring means is preferably of a length equal to the distance between the flanges 2, 2 of the tie. It is apparent that 35 if the member 12 extends from flange to flange of the tie, that it will be easily and securely held in place, for it is obvious that any rotation of the anchoring means would be impossible even if only one rivet should 40 be employed.

It is believed that the construction and

operation of the tie will be fully understood from the foregoing description.

In accordance with the patent statutes, I 45 have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

Having fully described the invention, what I claim as new and desire to secure by 50 Letters Patent is:

1. A metal cross tie, the body of said tie having the cross-sectional shape of channel iron, anchoring means attached to the bottom of the tie, said anchoring means having the cross-sectional shape of channel iron.

2. A metal cross tie, the body of said tie having the cross-sectional shape of channel iron, anchoring means attached to the bottom of the tie, said anchoring means having the cross-sectional shape of channel iron, and 55 said anchoring means extending below the bottom of said tie.

3. A metal cross tie, longitudinally extending down-turned flanges on said tie, hooked ends formed on said tie, rail clamping lugs mounted on the tie, wooden wedges adapted to be inserted between the rails and the hooked ends of the tie, anchoring means 60 extending between the downturned flanges, said anchoring means having the cross-sectional shape of channel iron and the downwardly extending flanges thereof being greater depth than the first-mentioned flanges and arranged substantially at right angles thereto.

JUSTUS J. ROSS.
